UNITED STATES PATENT OFFICE.

RUFUS A. FREEMAN, OF FLUSHING, NEW YORK, ASSIGNOR TO THE AUTOPRESS COMPANY, A CORPORATION OF NEW YORK.

PRINTING-PRESS CONTROLLER.

1,183,289.

Specification of Letters Patent. Patented May 16, 1916.

Application filed April 20, 1908. Serial No. 428,258.

To all whom it may concern:

Be it known that I, RUFUS A. FREEMAN, a citizen of the United States, and a resident of Flushing, Queens county, State of New York, have invented certain new and useful Improvements in Printing-Press Controllers, of which the following is a specification.

The invention relates to printing presses, and more particularly to presses in which the running of the press is controlled by the sheet, although in certain of its features the invention is applicable to other presses.

Objects of the invention are to provide for accurate and reliable control of the press by the fed-in sheets; to provide for such control in a press capable of running at very high speed; to provide devices for controlling the press by the sheet which are simple in construction and speedy and reliable in action; to provide simple and effective means for tripping the printing couple and to provide a sensitive and reliable control thereof by the fed-in sheets; to provide such means for throwing off the power; to provide means having the same characteristics for effecting a braking action; to provide for the actuation of all these from the fed-in sheet, and to provide for their joint actuation by the sheet.

These and other objects of invention will in part be obvious and will in part be set forth herein.

The invention consists in the novel parts, arrangements, improvements, and combinations herein shown and described.

The accompanying drawings, referred to herein and forming a part hereof, serve in connection with the description herewith to illustrate the principles of the invention.

Of the drawings: Figure 1 is a plan view of portions of a machine constructed in part in accordance with the principles of the invention; Fig. 2 is a vertical section on the line 2—2 of Fig. 1; Fig. 3 is a detail of certain parts on the line 3—3 of Fig. 1; and Fig. 4 is an elevation of parts of a printing press constructed in part in accordance with the principles of the invention. Figs. 4^a and 4^b are views of portions of the mechanism shown in Fig. 4 looking from the right of that figure.

In the embodiment of the invention illustrated, by way of example, in the accom-

panying drawings, the printing couple comprises a reciprocating bed and an oppositely reciprocating or traveling cylinder the latter of which members is indicated by the numeral 1. Means are provided in accordance with the invention for tripping one of said members and with the particular form of printing couple referred to, said tripping means are constructed and arranged to cooperate with means for causing the members of the printing couple to travel in one direction with the impression on and in the other direction with the impression off. In the present embodiment, said parts are constructed and arranged so that the cylinder is moved out of contact with the bed while the parts are traveling in one direction and is moved into contact therewith for the impression while they are traveling in the opposite direction. Any suitable or convenient means for effecting this movement may be employed, so far as regards many aspects of the invention, and in the present embodiment cylinder 1 is mounted in a frame carried upon the pillars 3 one pair at each side of the press. The pillars 3 are shown provided with lifting springs 3^a, housed in suitable casings formed integral with the main frame. These springs are arranged to hold up the pillars 3 and the impression cylinder therewith. The lower end of each pillar 3 is provided with a nut 7' which holds in place a cam 5 rotatably mounted on pillar 3 and provided with an arm 7. Above cam 5 and abutting against the spring casings to prevent upward movement, is a cam 4. Cams 4 and 5 are similar in construction, each being provided with a number of ridges 6 having one face perpendicular and the other beveled. Between these ridges are flat faces. These ridges and faces form in effect a series of teeth. The cams 5 are rocked through the arms 7 in timed relation to the operation of the press and cooperated to pull the pillars 3 downward when the ridges are sliding on each other until the flat faces are opposite each other. Similarly, when moved in the opposite direction, the cam 5 is turned until the ridges come into contact, when the springs 3^a move the pillars 3 upward. In the position illustrated in Fig. 4, cam 5 has been turned until the faces are in contact, so that the pillars 3 have been drawn down.

In the form illustrated, the arms 7 of cams 5 are connected by a link 8 connected to a lever 9 which is reciprocated through a pin 11 on lever 9, engaging recess 12 in a link 10, which, in turn, is moved by a cam 13 driven by a shaft suitably connected to the mechanism of the press. In the normal operation of the press and without the intervention of the mechanism about to be described, the cam 13 for each reciprocation of cylinder 1 would reciprocate the cams 5 once, thus first drawing down the cylinder and holding it down during a portion of its journey in one direction and permitting it to use and stay up for the remainder of the cycle.

It is desirable to provide means by which the cylinder is tripped or not brought into printing relation in the event no sheet is presented to cylinder 1. In the form illustrated, such a tripping means is provided, being sheet controlled in the manner to be hereinafter described. To enable this tripping mechanism to operate, there is provided a cam 15 rotating once for each cycle of the press and oscillating a bell crank 14, a roller on which is under the link 10. The cam 15 and bell crank 14 are arranged so that the link 10 is lifted to free the recess 12 from the pin 11 just before cam 13 starts to move link 10 to rock cams 5 to lower cylinder 1. The cam 15 holds link 10 up only for an instant and drops it before link 10 starts to move. Such action alone in no wise affects the operation of the raising and lowering of the cylinder. If, however, no sheet has been presented to the cylinder, a shaft 18 is oscillated at the instant link 10 is raised and this causes a hook lever 16 fastened thereto to swing so that its hook engages beneath a projection 17 on link 10. This prevents the recess 12 from engaging the pin 11 so that, as the link 10 moves, it does not affect the cams 5, thus leaving the cylinder 1 up or out of printing relation. The mechanism for rocking shaft 18 will be described hereinafter. The tripping arrangement so far described is much the same as that shown in the patent to Vierengle No. 1,072,883. Suitable means are provided for presenting sheets to said couple and so far as concerns many features of the invention said sheet-feeding means may be of any desired form.

In the present embodiment automatic sheet-feeding means are shown suitable for receiving sheets from an automatic sheet-separator, preferably such as is disclosed in my Patent No. 1,072,936, dated September 9, 1913. The illustrated form comprises traveling tapes 19 passing over rolls at each end. Drop rollers 20 are also shown mounted upon arms 21 carried upon a shaft 22. Fixed to the shaft 22 is shown an arm 23 in operative relation with a cam 24 held to the

cam by a spring 25 acting on the shaft 22. Suitable front gages or stops 26 are shown for positioning the sheet and then permitting it to be taken by the grippers on the impression cylinder. The front gages are shown mounted upon the shaft 38, and actuated by means of lever arms 28 and cam 39. Suitable top guide fingers, such as are shown at 27, may also be used if desired.

Actuating means for the tripping mechanism are provided and in accordance with certain principles of the invention the operation of said actuating means is controlled by the sheet which has been presented in position to be taken by the printing couple, the operation or non-operation of the tripping means being dependent upon whether the sheet is in position or not at the time the printing couple is ready to take the sheet. In the present embodiment said means comprises a member movable by the sheet to prevent the operation of the actuating means for the tripping mechanism and said member is further shown in this embodiment as movable by the sheet to engage the actuating member and hold it from its actuating movement.

While, so far as concerns certain features of the invention, the actuating means may be of any desired or convenient form, according to other features of the invention, said actuating means comprises a member under impulsion to actuate the tripping means but intermittently restrained therefrom by suitable means. In conjunction therewith there is provided a member movable by the sheet to control said impulsion member when it is not restrained by the restraining means. In the present embodiment also the restraining means acts upon said actuating means while the sheet is being printed, but when a sheet is to be taken by the printing couple said actuating means are under the control of the member movable by the sheet in position to be taken by the printing couple, so that in case no sheet is in position at the proper time the press may be tripped. The form of said actuating means comprised in the illustrated embodiment of the invention includes a spring-operated member for actuating the tripping means, said member being shown in the form of a slideable rod 30. In this embodiment said rod is further shown longitudinally slideable and is put under impulsion by a suitable spring, shown herein as a spring 31 coiled about said rod and acting between a collar 32 thereon and the press frame. An arm 33 is shown fast upon the shaft 18 and having its free end in operative relation with said rod 30. When said rod is moved by its spring it rocks the arm 33 to operate the tripping mechanism. It will be understood that in the particular embodiment of the invention illustrated the

tripping mechanism comprises the arm 33, rock shaft 18, and arm 16. The actuating means for the tripping mechanism comprises the spring-pressed rod 30.

5 The form of means for intermittently restraining the actuating means illustrated herewith comprises a lever 34 connected to the rod 30 by having its end engage a slot therein and in operative relation with a 10 suitably shaped cam 35. Said cam 35 is shown carried upon a suitable shaft 36 and is timed with the driving mechanism of the press. It will be seen that said mechanism serves also to put spring 31 under tension 15 when the lever 34 rides upon the high part of the cam.

The form of means shown in this embodiment to control the movement of said actuating means for the tripping means hereinbefore referred to comprises a member 37 movably mounted upon a suitable support. For convenience it is shown pivotally mounted upon the shaft 38 carrying the front guides 26. One end of the member 37 25 is shown arranged to be moved by a sheet at the front gages in position to be presented to the printing couple, thereby causing the other end to engage a recess 40 in the rod 30. The rod 30 is thus controlled 30 as to its movement by the sheet actuated member 37 and prevented from sliding with its spring when the restraining means comprising the lever 34 and cam 35, would permit of such movement. The cam 35 through 35 its lever 34 holds the rod 30 against the action of the spring 31, so that the end of member 37 may be moved freely into the recess 40 when member 37 is tilted by a sheet under its opposite end.

40 Suitable means are provided for driving the printing couple which may be of any suitable and convenient form. The particular form thereof constitutes no part of the present invention, and need not be described 45 in detail. Suitable means are provided for disconnecting the driving means, and in connection with this embodiment single means are provided for actuating the tripping means for the printing couple and the 50 disconnecting means for the driving power. Connected with the driving means is shown a clutch 41 and a clutch shifting lever 42. When said lever is unrestrained it will disconnect the driving means from the printing 55 couple. Suitable means are therefore provided for holding said lever to keep the clutch in the driving position or to release said lever to disconnect the driving means. The particular form of such means shown 60 herein comprises a bent lever 43 having a hooked end 44 engaging with a hook 45 upon the lever 42. The other end of the lever 43 is shown in operative relation with the end of the rod 30 so that when the rod 30 is 65 permitted to slide with its spring 31 it will

actuate both the arm 33 and lever 42, thus actuating both the tripping means and the means for disconnecting the power.

In certain of its features, the invention contemplates providing a brake and actuating means therefor and a member movable by the sheet to prevent operation of the brake actuating means. In this embodiment also a brake is provided actuated by the stored energy of the press. The brake controlling means is also shown in a form suitable for coöperating with the tripping means for the printing couple. In the drawings herewith a brake shoe 46 is shown adapted to act upon the fly-wheel 47, 8 said brake shoe 46 being mounted loosely upon a suitable support so as to be moved toward and from said wheel. An arm 57 is shown constructed and arranged to so move the brake shoe 46. A device for regulating the pressure between the arm 57 and brake shoe may be provided, such as the adjusting screw 48 shown in Fig. 4 of the drawings. The arm 57 is shown fast upon the shaft 49 which also carries fixed thereto 90 the arm 50. Connected pivotally with the free end of the arm 50 is a contact piece 51 having any suitable means to prevent it falling below the position shown in Fig. 4, such as a toe 51' arranged to contact with arm 50. The piece 51 may be swung upward but cannot fall below the level shown in Fig. 4. Said parts are constructed and arranged so that in case the link 10 is retracted by the cam 13 while in the 10 tripping position the lug 17 thereon will contact with the member 51 and the movement of the link 10 by the driving mechanism will apply the brake. The piece 51 is pivoted so that it will not resist the upward swing of link 10 by reason of the projection 17 being under the piece 51 when cam 15 operates.

The operation of the herein-described mechanism is substantially as follows: The 110 bed and cylinder are operated in a suitable manner so that they travel back and forth, the cylinder at the same time rolling upon the bed to print the sheet. The cam 13 in rotating reciprocates the link 10 and through 115 the lever 9 and connections serves to intermittently rock the small cams 5. By the coöperation of cams 4 and 5, together with the action of springs 3^a, in the manner hereinbefore described, the pillars 3 will be 120 raised and lowered, thus raising and lowering cylinder 1 and lower the pillars 3 thus raising and lowering the cylinder out of and into contact with the bed so that they travel in one direction in contact to print the sheet and in the opposite direction out of contact, in a well known manner. The bellcrank lever 14 is actuated by the cam 15 125 to alternately lift and drop the link 10 when it is substantially at the left hand end of 130

its movement. Normally the link 10 is raised and dropped again with the recess 12 engaging the pin 11. The hooked arm 16 is normally in a position to permit the link 10 to pass undisturbed. In case, however, the lever 33 is moved to rock the shaft 18 the arm 16 is swung inwardly so as to engage the lug 17 to prevent the dropping of the link 10. In such case the link 10 is reciprocated without moving the lever 9⁸ and its associated parts and the bed and cylinder travel their next stroke tripped.

As hereinbefore described, the rod 30 is impelled by its spring to move to the left, as shown in Fig. 1 of the drawings. This movement of the rod 30 serves to move the arm 33 and to rock the shaft 18. The cam 35 acting upon the lever 34 serves to put the spring 31 under tension and to restrain the rod 30 from its actuating movement while the lever 34 is riding upon the high part of the cam. This occurs while a sheet is being printed by the printing couple. As the printing couple is in position to take a new sheet the lever 34 rides upon the low part of the cam 35 and would permit the rod 30 to slide with its spring 31 to actuate the tripping mechanism. If, however, a sheet is present at the front gages in position to be taken, the member 37 is swung upon its axis and its end engages in the recess 40 and holds the rod 30 from its actuating movement. When the sheet is taken off by the printing couple the cam 35 has rotated so as to again restrain the member 30 as hereinabove described. In case, however, a sheet is not in position to be taken by the cylinder 1 at the proper time, the member 37 is not moved and the rod 30 is free to slide when released by the cam 35 and to actuate the tripping mechanism. If the press should be tripped and stopped, upon its being started again the cam 35 will return the rod 30 against its spring and thus put the spring under tension.

The operation of the power disconnecting means will be understood from the foregoing description. It may be stated briefly, referring especially to Figs. 1, 3 and 4 of the drawings, that the rod 30 when permitted to slide rocks the lever 43 and releases the lever 42, which in turn disconnects the clutch 41.

The operation of the brake mechanism will likewise be understood from the foregoing description. It has been stated that the engagement of the lug 17 by the arm 16 brings it in alignment with the contact piece 51, thus causing the link 10 and cam 13, acting through the arms 50 and 57 to apply the brake 46. The link 10 is lifted when projection 17 is under piece 51 which is swung upward thereby, but as link 10 moves from beneath piece 51, the latter

drops so as to be struck when projection 17 again moves to the left in Fig. 4.

It will be understood that, when the clutch 41 is disconnected, there will still be energy stored in the moving parts of the press, and particularly in the fly wheel 47. The function of the brake is to absorb this stored energy. As the cam 13, after the clutch 41 is disengaged, continues to turn by reason of this stored energy, the brake is applied by the same power which it has to absorb.

From all the foregoing it will be understood that a machine has been provided embodying the principles of the invention as set forth in the description and claims, and realizing the objects of the invention and the advantages herein set forth, together with other objects and advantages.

The invention, in its broader aspects, is not limited to the particular constructions shown, nor to any particular constructions by which it has been or may be carried into effect, as many changes may be made in the construction without departing from the main principles of the invention and without sacrificing its chief advantages.

What I desire to claim as my invention, and to secure by Letters Patent, is:

1. A printing press including in combination, sheet-presenting means, a printing member, mechanism for tripping said printing member, means for actuating said tripping mechanism, a member extending into the path of a sheet in the control of said presenting means and arranged to be operated by the sheet to render said actuating means inoperative, and mechanism for retaining said actuating means in its inoperative position while the sheet-operated member is being operated.

2. A printing press including in combination, sheet-presenting means, a printing member, mechanism for tripping said printing member, means for actuating said tripping mechanism, a member extending into the path of a sheet in the control of said presenting means and arranged to be operated by the sheet to engage said actuating means and hold it from its actuating movement, and mechanism for retaining said actuating means in its inoperative position while the sheet-operated member is being operated.

3. A printing press including in combination, sheet-presenting means, a printing member, mechanism for tripping said printing member, a member movable to actuate said tripping mechanism, means for restraining said member from such movement while the sheet is being presented, and a member operated by the sheet to control the movable member when the said restraining means is inactive.

4. A printing press including in combination, sheet-presenting means, a printing

member, mechanism for tripping said printing member, a member, under impulsion while the sheet is being presented, to actuate said tripping means, means for intermittently restraining said member, and a member operated by the sheet to control the said impulsion member when the said restraining means is inactive.

5. A printing press including in combination, sheet-presenting means, a printing member, mechanism for tripping said printing member, a member for actuating said tripping mechanism, a spring to move said member to cause it to actuate said mechanism, a member movable by the sheet to control said actuating member, and means to prevent the operation of said spring while said movable member is moved by the sheet.

6. A printing press including in combination, sheet-presenting means, a printing member, mechanism for driving the press, means for tripping said printing member, a spring-operated member for actuating said tripping means, a cam timed with said driving mechanism for putting said spring under stress while the sheet is being presented, and means operated by the sheet to control the movement of said spring-operated member.

20 7. A printing press including in combination, sheet-presenting means, a printing member, mechanism for driving the press, means for tripping said printing member, a 25 slideable spring-operated member for operating said tripping means, a cam timed with the said driving mechanism for putting said spring under stress while the sheet is being presented, and means operated by the sheet to engage the said slideable member to hold 30 it against the pressure of the spring.

8. A printing press including in combination, sheet-presenting means, a printing member, driving mechanism for the press, means for tripping said printing member, a 45 longitudinally slideable spring-pressed rod for actuating said tripping means, a cam connecting to the said driving means, connections between said slideable rod and cam for sliding the rod against its spring and 50 permitting it to slide with its spring, and a member movable by the sheet to prevent the rod sliding with its spring.

55 9. A printing press including in combination, sheet-presenting means, a printing member, means for driving the press, means for tripping said printing member, a longitudinally slideable spring-pressed rod for actuating said tripping means, a cam connecting to the said driving means, connections 60 between said slideable rod and cam for sliding the rod against its spring and permitting it to slide with its spring, and a member operated by the sheet into engagement

with said slideable rod to prevent the rod sliding with its spring.

65 10. A printing press including in combination, sheet-presenting means, a printing member, mechanism for driving the press, means for tripping said printing member, a brake for stopping the press, actuating 70 means for said tripping means, means actuated by the stored energy of the press to apply the brake, and a member movable by the sheet to control the said actuating means for the tripping means and brake.

75 11. A printing press including in combination, sheet-presenting means, a printing member, mechanism for driving the press, means for tripping said member, means for disconnecting said driving means, single 80 means for actuating the tripping means and the disconnecting means, means movable by the sheet to prevent the operation of said actuating means, and means for automatically restoring said actuating means to operative condition and for restraining said actuating means while said movable means is being moved by the sheet.

85 12. A printing press including in combination, sheet-presenting means, a printing member, means for tripping said member, actuating means for said tripping means, a member operable by the sheet from a position normally disengaged from said actuating means into engagement therewith to 90 arrest movement of said actuating means, and means for restraining said actuating means while said movable member is moved by the sheet.

95 13. A printing press including in combination, sheet-presenting means, a printing member, means for tripping said member, actuating means for said tripping means, a member movable by the sheet into interlocking engagement with said actuating means 100 to prevent movement thereof, and means for restraining said actuating means while said movable member is moved by the sheet.

105 14. A printing press including in combination, sheet-presenting means, a printing member, tripping means for said member, means for actuating said tripping means, a trip-controlling member actuated by the sheet into cooperative engagement with said actuating means to stop said member while moving to a position to operate said tripping means, and means for restraining said actuating means while said movable member is moved by the sheet.

110 15. In testimony whereof, I have signed my name to this specification, in the presence of two subscribing witnesses.

RUFUS A. FREEMAN.
